MITCHELL L. FYKSE AND ROGER SHERMAN HOAR, OF SOUTH MILWAUKEE, WISCONSIN,
ASSIGNORS TO BUCYBUS-ERIE COMPANY, OF SOUTH MILWAUKEE, WISCONSIN, A
CORPORATION OF DELAWARE

LUMPING DEVICE FOR BACK-DIGGING SHOVELS

Application filed December 4, 1929. Serial No. 411,473.

Our invention relates to new and useful improvements in dumping devices for back digging shovels.

Back digging shovels are well known in the excavating art. They are characterized by a dipper mounted on the lower end of a handle, which is pivoted intermediate its ends on the outer end of the boom, the inner end of the boom being pivoted to the frame of the machine. The shovel faces toward the machine. On the main frame of the machine is a two-drum winch, from which one rope, associated with the dipper, tends to swing the dipper toward the machine. The other rope of the winch is associated with the upper end of the dipper handle and tends both to hoist the boom and to swing the dipper away from the machine.

The principal object of our invention is to provide a swiveled dipper for such shovel, together with means for holding this dipper rigid with respect to the handle during digging, and for tilting the dipper at will to dump.

Further objects and advantages of our invention will be readily evident, as the description progresses.

The invention consists in the novel parts, and in the combinations and arrangements thereof, which are defined in the appended claims, and of which one embodiment is exemplified in the accompanying drawing, which are hereinafter particularly described and explained.

Throughout the description, the same reference number is applied to the same member or to similar members.

The single figure is a side elevation of a power shovel embodying our invention.

Referring to the drawing, it will be seen that 11 is the main base of a power shovel, supporting a boom 12, an A-frame 13, and a main winch 14. The winch includes two drums 15 and 16. The boom 12 is pivoted to the base 11 at 17.

A handle 18 is pivoted to the boom 12 at 19. The handle carries at its upper end a sheave 20, on the inner side of its lower end a sheave 21 and a stop 22, and at the outer side 50 of its lower end a sheave 23.

A dipper 24 is pivoted on the lower end of the handle 18 at 25. This dipper is open toward the main base 11, and carries at its open end a rope anchorage 26, and at its closed end a rope anchorage 27 and a cam-shaped guide 28.

There is a sheave 29 on the A-frame 13.

A rope 30 passes from the anchorage 27 over the guide 28, under the sheave 23, over the sheave 20, over the sheave 29, to the winch drum 15. This rope tends to hoist the boom 12, and to swing the handle 18 in a counterclockwise direction about the pivot 19, and to tilt the dipper 24 in a counterclockwise direction about the pivot 25.

A rope 31 passes from the anchorage 26, over the sheave 21, to the winch drum 16. This rope tends to hold the dipper 24 in rigid digging position against the stop 22, and to swing the handle 18 clockwise about the pivot 19.

These ropes should be so disposed, that the rope 31, during digging, will always have a greater tendency to tilt the dipper about the pivot 25, than does the rope 30.

Accordingly, when tension is in both ropes, during any operation of the shovel, the dipper will remain against the stop 22, and the tendency of the rope 30 to tilt the dipper, and thus dump it, will be ineffective.

From an anchorage 32 on the handle 18, a rope 33 runs to an anchorage on a drum 34 mounted on the boom 12. From an anchorage on this same drum, a rope 35 runs over a sheave 36 on the A-frame 13, to a light counterweight 37.

Integral with the rope drum 34 is a brake drum 38, around which is disposed a brake band 39, which may be set by means of the rope 40 and lever 41.

During the ordinary operations of the dipper, the weight 37 serves just barely to keep the ropes 33 and 35 taut, thus preventing them from becoming snarled and interfering with the rest of the mechanism.

When the dipper has been raised to the dumping position above the dump cart or spoil bank, the brake 39 is set by the lever 41. If then the rope 30 is pulled in and the rope 31 paid out, the dipper will tilt about its pivot 100

25, thus dumping its contents. The brake can then be released, and the pull on rope 31 will restore the dipper to its normal digging position.

5 It is to be noted that although the setting of the brake 39 inhibits positively merely the tendency of rope 30 to swing the dipper handle 18, and not its tendency to hoist the boom 12; nevertheless a proper relative tension on ropes 30 and 31 by the operator, during dumping, will inhibit this last-named tendency as well.

Throughout the description and the claims we have, for clarity, employed the word 15 "hoist" to describe rotating the boom 12 in a vertical plane about its pivot 17; the word "swing" to describe rotating the handle 18 in a vertical plane about its pivot 19; and the word "tilt" to describe rotating the dipper 24 20 in a vertical plane about its pivot 25. Accordingly when, in the claims, we refer to means for rendering ineffective these two tendencies, we have in mind the operation described in this paragraph.

25 We wish it to be understood that our invention is not to be limited to the specific form or arrangement of parts hereinbefore described, except with respect to any claim which imposes such limitations.

30 We claim:

1. In a back-digging shovel, the combination of: a main frame; a boom, pivoted at its lower end to the frame, for hoisting in a vertical plane about its pivot; a dipper handle, pivoted intermediate its ends at the outer end of the boom, for swinging in a vertical plane about its pivot; a digging dipper pivoted on the lower end of the handle, and facing toward the frame; single means 35 tending to hoist the boom, swing the dipper away from the frame, and tilt the dipper about its pivot for dumping; means for rendering ineffective, at will, the hoisting and swinging tendencies of the last-named 40 means; and single means for tilting the dipper about its pivot to digging position and for swinging the dipper toward the frame.

2. In a back-digging shovel, the combination of: a main frame; a boom, pivoted at its 50 lower end to the frame, for hoisting in a vertical plane about its pivot; a dipper handle, pivoted intermediate its ends at the outer end of the boom, for swinging in a vertical plane about its pivot; a digging dipper pivoted on the lower end of the handle, and facing toward the frame; two winch drums; a sheave on the upper end of the dipper handle; a rope, running from the bottom of the dipper, over this sheave, to one drum; a sheave 55 on that side of the lower end of the handle nearer toward the base; a rope running from the front of the dipper, over this sheave, to the other drum; and means for rendering ineffective, at will, the hoisting and swinging 60 tendencies of the first-named rope.

3. In a back-digging shovel, the combination of: a main frame; a boom, pivoted at its lower end to the frame, for hoisting in a vertical plane about its pivot; a dipper handle, pivoted intermediate its ends at the outer end of the boom, for swinging in a vertical plane about its pivot; a digging dipper, pivoted on the lower end of the handle, and facing toward the frame; two winch drums; a sheave on the upper end of the dipper handle; a rope, running from the bottom of the dipper, over this sheave, to one drum; a sheave on that side of the lower end of the handle nearer toward the base; a rope, running from the front of the dipper, over this sheave, to the other drum; means for limiting the tilting of the dipper under the influence of the last-named rope; and means for rendering ineffective, at will, the hoisting and swinging tendencies of the first-named rope. 70

4. In a back-digging shovel, the combination of: a main frame; a boom, pivoted at its lower end to the frame, for hoisting in a vertical plane about its pivot; a dipper handle, pivoted intermediate its ends at the outer end of the boom, for swinging in a vertical plane about its pivot; a digging dipper pivoted on the lower end of the handle, and facing toward the frame; two winch drums; a sheave on the upper end of the dipper handle; a rope, running from the bottom of the dipper, over this sheave, to one drum; means for limiting the tilting of the dipper under the influence of the last-named rope; and means for rendering ineffective, at will, the hoisting and swinging tendencies of the first-named rope. 75

80

5. In a back-digging shovel, the combination of: a main frame; a boom, pivoted at its lower end to the frame, for hoisting in a vertical plane about its pivot; a dipper handle, pivoted intermediate its ends at the outer end of the boom, for swinging in a vertical plane about its pivot; a digging dipper pivoted on the lower end of the handle, and facing toward the frame; two winch drums; a sheave on the upper end of the dipper handle; a rope, running from the bottom of the dipper, over this sheave, to one drum; a guide on the bottom of the dipper, over which guide this rope is adapted to pass; a sheave on that side of the lower end of the handle nearer toward the base; a rope, running from the front of the dipper, over this sheave, to the other drum; and means for rendering ineffective, at will, the hoisting and swinging tendencies of the first-named rope. 85

lower end to the frame, for hoisting in a vertical plane about its pivot; a dipper handle, pivoted intermediate its ends at the outer end of the boom, for swinging in a vertical plane about its pivot; a digging dipper pivoted on the lower end of the handle, and facing toward the frame; two winch drums; a sheave on the upper end of the dipper handle; a rope, running from the bottom of the dipper, over this sheave, to one drum; a sheave on that side of the lower end of the handle nearer toward the base; a rope, running from the front of the dipper, over this sheave, to the other drum; and means for rendering ineffective, at will, the hoisting and swinging tendencies of the first-named rope, this means consisting in a rope-drum, a brake to prevent the rotation of this drum, a rope passing from the lower portion of the handle to an anchorage on this drum, and means for taking up the slack in this rope.

7. In a back-digging shovel, the combination of: a main frame; a boom, pivoted at its lower end to the frame, for hoisting in a vertical plane about its pivot; a dipper handle, pivoted intermediate its ends at the outer end of the boom, for swinging in a vertical plane about its pivot; a digging dipper, pivoted on the lower end of the handle, and facing toward the frame; two winch drums; a sheave on the upper end of the dipper handle; a rope, running from the bottom of the dipper, over this sheave, to one drum; a sheave on that side of the lower end of the handle nearer toward the frame; a rope, running from the front of the dipper, over this sheave, to the other drum; means for limiting the tilting of the dipper under the influence of the last-named rope; and means for rendering ineffective, at will, the hoisting and swinging tendencies of the first-named rope, this means consisting in a rope drum, a brake to prevent the rotation of this drum, a rope passing from the lower portion of the handle to an anchorage on this drum, and means for taking up the slack in this rope.

8. In a back-digging shovel, the combination of: a main frame; a boom, pivoted at its lower end to the frame, for hoisting in a vertical plane about its pivot; a dipper handle, pivoted intermediate its ends at the outer end of the boom, for swinging in a vertical plane about its pivot; a digging dipper pivoted on the lower end of the handle, and facing toward the frame; two winch drums; a sheave on the upper end of the dipper handle; a rope, running from the bottom of the dipper, over this sheave to one drum; a guide on the bottom of the dipper, over which guide this rope is adapted to pass; a sheave on that side of the lower end of the handle nearer toward the frame; a rope, running from the front of the dipper, over this sheave, to the other drum; and means for rendering ineffective, at will, the hoisting and swinging tendencies of the first-named rope, this means consisting in a rope-drum, a brake to prevent the rotation of this drum, a rope passing from the lower portion of the handle to an anchorage on this drum, and means for taking up the slack in this rope.

9. In a back-digging shovel, the combination of: a main frame; a boom, pivoted at its lower end to the frame, for hoisting in a vertical plane about its pivot; a dipper handle, pivoted intermediate its ends at the outer end of the boom, for swinging in a vertical plane about its pivot; a digging dipper pivoted on the lower end of the handle, and facing toward the frame; two winch drums; a sheave on the upper end of the dipper handle; a rope, running from the bottom of the dipper, over this sheave, to one drum; a guide on the bottom of the dipper, over which guide this rope is adapted to pass; a sheave on that side of the lower end of the handle nearer toward the base; a rope, running from the front of the dipper, over this sheave, to the other drum; and means for taking up the slack in this rope.

9. In a back-digging shovel, the combination of: a main frame; a boom, pivoted at its lower end to the frame, for hoisting in a vertical plane about its pivot; a dipper handle, pivoted intermediate its ends at the outer end of the boom, for swinging in a vertical plane about its pivot; a digging dipper pivoted on the lower end of the handle, and facing toward the frame; two winch drums; a sheave on the upper end of the dipper handle; a rope, running from the bottom of the dipper, over this sheave, to one drum; a guide on the bottom of the dipper, over which guide this rope is adapted to pass; a sheave on that side of the lower end of the handle nearer toward the base; a rope, running from the front of the dipper, over this sheave, to the other drum; and means for limiting the tilting of the dipper under the influence of the last-named rope; and means for rendering ineffective, at will, the hoisting and swinging tendencies of the first-named rope, this means consisting in a rope drum, a brake to prevent the rotation of this drum, a rope passing from the lower portion of the handle to an anchorage on this drum, and means for taking up the slack in this rope.

In testimony whereof we affix our signatures.

MITCHELL L. FYKSE.
ROGER SHERMAN HOAR.
